DISPLAY STAND AND SHELVING

Filed Aug. 26, 1930

By Clarence L. Foretich,
Frank A. Nealeman, Attorney

UNITED STATES PATENT OFFICE

CLARENCE L. FORETICH, OF WARREN, ARKANSAS

DISPLAY STAND AND SHELVING

Application filed August 26, 1930. Serial No. 477,879.

This invention relates to new, useful and economical improvements in the form of a multi-use self supporting joint, as illustrated in the drawings, for display stands, shelving and the like.

This invention furthermore relates to novel means for producing uprights having shelf anchoring means in which provision is made for expeditiously applying and removing the shelves.

In so far as this support joint, to be practical in useful effect, it must represent precision in workmanship. In all cases it is to be produced in wood, sheet or malleable metals or a combination of both, and the forms and arrangements of parts illustrated and described should be adhered to closely.

It is a further object of this invention to produce a shelf preferably made of wood wherein by forming slots in faces of posts or uprights, seats may be formed in which the edges of shelves may be inserted and held against accidental displacement, it being the purpose of the inventor furthermore to provide a device in which shelves are formed by the usual planing methods whereby a tongue-like flange is formed at one edge adapted to interlock with the walls of the recesses or seats in the posts or uprights.

Provision is therefore made in this invention for utilizing wood which can be expeditiously shaped by straight line cutting to produce an effective shelf, bracket or the like which may be used for any of the well known purposes including window displays.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in perspective of a fragment of a shelf in partially assembled relation to a part of a post or upright;

Figure 2 illustrates a view in end elevation of the assembled unit;

Figure 3 illustrates a perspective view of one of the shelves;

Figure 4 illustrates a top plan view of one of the assemblies; and

Figure 5 illustrates an end view thereof. 55

In these drawings 10 denotes the post or upright which may be employed for supporting shelves such as 11 near the ends of the shelf or between its ends as would be the method employed in constructing a bracket 60 where one support is utilized.

Each support may be provided with one or more half dove tail grooves such as 12 preferably having a straight bottom wall 13 and a beveled or inclined upper wall 14. 65

The shelves 11 each are to be employed in association with the supports for a curved lower corner 16 at one edge and a beveled or inclined upper surface 17 forming a flange or lip, the outer edge of which is on a plane 70 above the general surface of the shelf.

Shelves are applied to the half dove tail grooves by manipulating them in order that they will occupy an inclined position in order that the flanged edge may enter the restricted opening of the half dove tail groove a predetermined distance and the shelves are then gradually lowered at their outer edge and they are held in horizontal positions by reason of the engagement of the beveled surface 17 of the shelf with the beveled upper wall of the half dove tail groove, the curved lower corner 10 providing a clearance which permits the insertion of the shelf in the said slots. 75

By reason of the arrangement of parts, the shelf is held in place by gravity and there is no requirement for a third member for the purpose of holding the parts in their assembled relation as display fixtures, household novelties or the like. 80

The member as described can be formed or made by straight line machine work which insures rapid production at comparatively small cost. 85

The uprights may be supported by two or more legs 18 having beveled upper ends 19 which fit against the sides of the uprights and the lower end 20 of each leg is appropriately beveled to rest on the floor or other 100

support. The legs are connected to the uprights by hinges whose leaves 21 and 22 are secured to the leg and upright respectively by suitable fastenings with the pintle 23 of the hinge at the lower edge of the upper end of each leg. This arrangement of parts permits the legs to be folded so that they lie parallel with the sides of the uprights or posts and if desired two, three or four legs may be 10 provided, one on each side in order to produce firm supports for the said uprights.

I claim—

1. In a fixture of the character described, an upright having a half dove tail groove 15 merging with one of its edges, the lower wall of the half dove tail groove being at right angles to the said edge and the upper wall thereof being inclined toward said edge, a shelf having a curved lower corner at one 20 edge and an inclined upper surface, the edge of the shelf having the curved corner and inclined surface being insertable in the said half dove tail groove with the inclined surface of the shelf engaging the inclined wall of the 25 groove whereby the shelf is held at right angles to the support.

2. In a fixture of the character described, an upright having an approximately half dove-tail groove the front of which merges 30 with one of its edges, the lower wall of said groove being at right angles to the said edge approximately throughout its surface, and the upper wall thereof at the rear of the groove being at an angle to the said edge with 35 its highest point at the rear of said groove, a shelf having an inner edge adapted to be inserted in the groove from the front thereof and having a restricted lower corner to provide a clearance to permit the shelf to 40 enter the groove when in an inclined position, the upper corner of the inner edge of the shelf having a lip whose upper surface is substantially complementary in shape to that of the surface of the upper wall of the groove 45 which it engages.

CLARENCE L. FORETICH.
